CARBURETOR

Harry Estel Shultz, West Los Angeles, Calif.

Application May 1, 1950, Serial No. 159,272

3 Claims. (Cl. 261—50)

1

This invention relates to carburetors for use with internal combustion engines and the like, which are used to form an explosive mixture of air and gaseous fuel such as gasoline or kerosene.

An object of the invention is to provide a carburetor of extreme simplicity of structure having a minimum number of operating parts due to the elimination of the usual "control" for the liquid fuel.

It is a further object of the invention to provide a carburetor in which the relative amount of gasoline vapor and air may be easily regulated, and which carburetor is provided with means whereby the suction from the engine automatically maintains a uniform richness of mixture by increasing or decreasing the amount of air and gasoline vapor delivered to the mixing chamber.

Still another object of the invention is to provide a carburetor whereby the relative proportions of gasoline and air may be regulated and the uniformity of the mixture maintained without the need of a float.

Still further objects of the invention reside in the provision of a carburetor that is strong, durable, highly efficient in operation, simple in construction and manufacture, capable of being readily installed on the manifold of the automotive vehicle, and which is relatively inexpensive.

These, together with the various ancillary objects of the invention which will become apparent as the following description proceeds, are attained by this carburetor, a preferred embodiment of which has been illustrated in the accompanying drawings, by way of example only, wherein:

Figure 1 is a vertical sectional view of the invention showing the component parts thereof;

Figure 2 is a horizontal sectional view as taken along the line 2—2 of Figure 1;

Figure 3 is a horizontal sectional view as taken along the line 3—3 in Figure 1;

Figure 4 is an elevational view of the central member comprising an important element of the carburetor;

Figures 5 and 6 are elevational details showing means for the fuel outlet;

Figure 7 is an elevational view of the fuel mixing element of the carburetor; and

Figure 8 is a horizontal sectional view as taken along the line 8—8 in Figure 7.

With continuing reference to the accompanying drawings wherein like reference numerals designate similar parts throughout the various views, reference numeral 10 generally designates the improved carburetor comprising the present invention.

The carburetor 10 includes a lower chamber 12 having a flange 14 for securing the carburetor to the manifold of the internal combustion engine.

2

retor to the manifold of the internal combustion engine. A cylindrical body 16 is integrally formed with the chamber 12 and is in communication with the atmosphere. Mounted on the lower chamber 12 is an upper chamber 18 which is provided with a bottom wall or flange 20. A gasket 22 is positioned between the flange 20 and the upper wall of the chamber 12 and screws such as those indicated at 24 are used to hold the upper chamber 18 in air-tight relationship with the lower chamber 12.

Supported by the bottom wall 20 is a central member 26 which is held securely in position by screws 28. A gasket 30 is provided to insure an air-tight seal. The central member 26 is provided with an upper flange 32 on which a lid 34 may be positioned for engagement with the upper edge of the chamber wall 18. Gaskets 36 and 38 are provided between the upper chamber wall 18 and the flange 32 so as to insure the air-tight seal. As the upper end of the central member 26 is threaded as at 40, a holding nut 42 is provided for securely fastening the lid 34 in position.

A vertical passage 44 is formed in the central member 26 and a needle valve 46 is positioned within an enlarged opening of the passage for controlling the flow of fuel from the upper chamber through the axial or transverse passage 50 in the central member. A gasoline intake tube 52 is provided and attached to the central member 26 in communication with the vertical passageway 44. The needle valve 46 is held in position by a packing nut 54 and is controlled by a handle 56. In the central member 26 and controlling the vertical passage 44 is a shaft 58 having a transverse opening 60 therein thus creating a valve for controlling the flow of fuel from the upper chamber 18 through the passageway 44. Secured to the shaft 58 is a control arm 62 which is connected to a suitable link mechanism 64 to a bifurcated element 66 attached to a butterfly valve 68 operatively controlled by an arm 70 actuated by the throttle of the internal combustion engine. A screw-actuated valve control screw 72 is provided to pre-set the fuel and gas supply ratio.

Threadedly secured to the central member 26 and forming a portion thereof is a fuel mixing element 74 which includes a tubular member 76 having a plurality of angularly disposed slots 78 therein, which slots are disposed at an angle of 40 degrees from the vertical in order to break up the fuel and to permit the mixing thereof with the intake air from the cylindrical body 16.

A choke operated butterfly valve 80 is mounted in the body 16 and is controlled by the choke operated lever arm 82. The butterfly valves 80 and 68 permit or prevent the passage of air into the lower or mixing chamber 12 and the gasoline

intake line 84 permits the passage of fuel from the gasoline tank into the fuel bowl or upper chamber 18.

The carburetor comprising the present invention operates by motor suction alone, not requiring an external gasoline pump. The valve controlled butterfly valve 68 and hence the fuel regulator valve 60 is opened and the choke butterfly valve 82 is normally closed upon starting of the engine, thus closing the intake vacuum to act through the needle valve 46. The vacuum in the intake manifold draws the gasoline through the gasoline supply line into the gas bowl or chamber 18. The manifold suction first draws all of the air out of the gasoline chamber and the gas line, and then fills the entire upper chamber with gasoline. Then as much gasoline is needed for the engine and no more is drawn through the gasoline intake line 52 into the vertical passageway 44. Passing through the valve 60 which controls the amount of gasoline reaching the air gas mixing element 78, the gasoline is carried out in a circular member through the element 78. After the vacuum has filled the gasoline bowl or chamber 18 and enough gasoline has been drawn down into the manifold to begin combustion, the choke butterfly is opened. As the valve 60 is opened increasing the flow of fuel, the butterfly valve 68 is also opened allowing a greater supply of air. As the speed of the engine increases the engine demand increases creating a greater supply of both air through the valve controlled butterfly valve and the gasoline through the valve 68. The throttle maintains a state of equilibrium between these two valves and thus regulate the speed of the engine.

Since from the foregoing the construction and advantages of this carburetor are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications and equivalents may be readily resorted to which fall within the scope of the appended claims.

Having described the invention, what is claimed as new is:

1. A carburetor comprising a lower chamber having an outwardly extending cylindrical body connected thereto and forming a passageway for air, an upper chamber positioned on said lower chamber, said upper chamber being adapted to contain fuel, the bottom wall of said upper chamber being provided with an aperture, a central member supported by said bottom wall of said upper chamber extending into said lower chamber, a substantially vertical passage in said member and having a needle valve seat, a first valve journaled in said member for controlling the flow of fuel through said passage, a transverse passage in said member communicating with said vertical passage and opening into said upper chamber, a needle valve arranged to be disposed on said seat for controlling the flow of fuel through said vertical passage and hence said transverse passage, a butterfly valve in said body, and means operatively connecting said butterfly valve and said first valve to control the amount of air permitted to pass into said lower chamber relative to the amount of fuel permitted to pass from said upper chamber to said lower chamber, said member including a mixing element com-

5 prising a hollow tubular member in communication with said vertical passage and located below said first valve and said needle valve and in said lower chamber, and a plurality of slots angularly disposed in said tubular member for the conduction flow of fuel therefrom.

2. A carburetor comprising a lower chamber having an outwardly extending cylindrical body connected thereto and forming a passageway for air, an upper chamber adapted to contain fuel positioned on said lower chamber, the bottom wall of said upper chamber being provided with an aperture, a central member supported by said bottom wall of said upper chamber extending into said lower chamber, a substantially vertical passage in said member and having a needle valve seat, a first valve journaled in said member for controlling the flow of fuel through passage, a transverse passage in said member communicating with said vertical passage and opening into said upper chamber, a needle valve arranged to be disposed on said seat for controlling the flow of fuel through said vertical passage and hence said transverse passage, a butterfly valve in said body, and means operatively connecting said butterfly valve and said first valve to control the amount of air permitted to pass into said lower chamber relative to the amount of fuel permitted to pass from said upper chamber to said lower chamber, said central member including a mixing element mounted at its lower end.

3. A carburetor comprising a lower chamber having an outwardly extending cylindrical body connected thereto and forming a passageway for air, an upper chamber adapted to contain fuel positioned on said lower chamber, the bottom wall of said upper chamber being provided with an aperture, a central member supported by said bottom wall of said upper chamber extending into said lower chamber, a substantially vertical passage in said member and having a needle valve seat, a first valve journaled in said member for controlling the flow of fuel through said passage, a transverse passage in said member communicating with said vertical passage and opening into said upper chamber, a needle valve arranged to be disposed on said seat for controlling the flow of fuel through said vertical passage and hence said transverse passage, a butterfly valve in said body, and means operatively connecting said butterfly valve and said first valve to control the amount of air permitted to pass into said lower chamber relative to the amount of fuel permitted to pass from said upper chamber to said lower chamber, said central member including a mixing element mounted at its lower end, said first valve is in the form of a transverse shaft having a transverse opening therethrough, said opening being triangular in cross-section at one end thereof and oval in cross section at the other end.
